(57) **CLAIM**

The ornamental design for infant clothing, as shown and described.

DESCRIPTION

FIG. 1 is a front elevational view of the infant clothing showing my new design;

FIG. 2 is a partially opened front elevational view of FIG. 1;

FIG. 3 is a rear elevational view of FIG. 1;

FIG. 4 is a fully opened front elevational view of FIG. 1; and, FIG. 5 is a side elevational view of FIG. 1.

The broken line showing on the outer periphery of the infant clothing indicate the stitching on the clothing but forms no part of the claimed design.
